UNITED STATES PATENT OFFICE.

LINVILLE V. LONG, OF BOWERSTON, OHIO, ASSIGNOR OF ONE-HALF TO
JAMES A. McKEAN, OF BOWERSTON, OHIO.

HOSE-CO尤PLING.

SPECIFICATION forming part of Letters Patent No. 752,085, dated February 16, 1904

Application filed June 17, 1903. Serial No. 161,946. (No model.)

To all whom it may concern:

Be it known that I, LINVILLE V. LONG, a citizen of the United States, residing at Bowers-
ton, in the county of Harrison and State of
Ohio, have invented a new and useful Hose-
Coupling, of which the following is a specifica-
tion.

The invention relates to improvements in
hose-couplings.

10 The object of the present invention is to im-
prove the construction of hose-couplings and
to provide a simple, inexpensive, and efficient
one of great strength and durability in which
the parts will always be in proper position to
15 enable a hose to be readily coupled without
turning or twisting the lengths thereof.

A further object of the invention is to pro-
vide a hose-coupling which will enable hose
20 to be rapidly coupled and uncoupled and
which will permit the same to be dragged over
streets, curbing, fences, and other obstruc-
tions without liability of becoming acciden-
tally uncoupled.

It is also the object of the invention to pro-
25 vide a hose-coupling adapted to exert a direct
pull on its sections, to prevent any binding or
frictional contact of the sections on each other,
and the consequent resistance to such move-
ment, and capable of enabling a steam, water,
30 and air tight joint to be readily made.

With these and other objects in view the in-
vention consists in the construction and novel
combination and arrangement of parts here-
inafter fully described, illustrated in the ac-
35 companying drawings, and pointed out in the
claims hereto appended, it being understood
that various changes in the form, proportion,
size, and minor details of construction within
the scope of the claims may be resorted to with-
40 out departing from the spirit or sacrificing any
of the advantages of the invention.

In the drawings, Figure 1 is a side elevation
of a hose-coupling constructed in accord-
ance with this invention, the parts being shown
45 locked in full lines and unlocked in dotted
lines. Fig. 2 is a longitudinal sectional view.
Fig. 3 is a transverse sectional view on the
line 3 3 of Fig. 2. Fig. 4 is a detail perspec-
tive view of the locking mechanism.

Like numerals of reference designate corre- 50
sponding parts in all the figures of the draw-
ings.

1 and 2 designate sections preferably con-
structed of cast malleable iron or other suit-
able metal and provided with outer portions 55
3 and 4 adapted to receive hose in the ordi-
nary manner, and these outer portions may be
smooth, as shown in the accompanying draw-
ings, or they may be corrugated or provided
with dull threads to prevent the hose from 60
slipping. Any means may be employed for
securing the hose to the outer portions 3 and
4 of the sections.

The section 1 is provided with a smooth in-
ner portion 5, which is adapted to fit into the 65
adjacent inner portion 6 of the section 2, and
the latter is enlarged, as shown, to receive the
section 1 and to provide an exterior annular
shoulder 7. The exterior annular shoulder 7
is inwardly beveled or undercut, as clearly 70
shown in Fig. 2, to receive and interlock with
a curved yoke 8, which conforms to the con-
figuration of the section 2 and which is beveled
at its inner engaging edge 9 to fit the beveled
or undercut portion of the section 2. The 75
yoke is rigidly secured to a pair of side bars
10, which are pivoted to the sides 11 of a
forked or bifurcated operating-lever 12. The
sides of the forked or bifurcated operating-
lever 12 are adapted to straddle the section 1 80
of the coupling, and they are pivoted near
their outer ends by rivets 13 or other suitable
fastening devices to a collar 14. The sides
11 of the forked or bifurcated lever form
short outer arms 15, which are pivoted to the 85
adjacent ends of the side bars 10 by rivets 16
or other suitable fastening devices.

The collar 14, which is arranged on the sec-
tion 1 of the coupling, is adapted to rotate
freely thereon to enable any adjustment of the 90
locking mechanism to be effected without turn-
ing or twisting the hose. The collar is ar-
ranged contiguous to an annular enlargement
17, located between the ends of the section 1
and provided with an annular groove 18, re- 95
ceiving the engaging portions of a pair of L-
shaped arms 19. The L-shaped arms 19, which
are located at diametrically opposite points,

are secured by screws 20 or other suitable fastening devices to the collar, and they extend over the adjacent portion of the annular enlargement and project into the annular groove thereof. By this construction the collar is swiveled on the section 1 and is adapted to rotate freely. Instead of swiveling the collar to the section 1 by means of the L-shaped arms suitable stops, such as set-screws 5 or the like, may be mounted on the section 1 at the outer side of the collar to confine the same in its position contiguous to the annular enlargement.

The lever when viewed in side elevation 15 is approximately sigmoidly curved, as illustrated in Fig. 2 of the drawings, to enable the outer portion to lie close to the coupling when the parts are locked and to present a smooth exterior to enable a hose to be dragged along 20 a street, over curbs, and rough places without liability of accidentally unlocking the sections. The coupling will permit a hose to be dragged over fences and to be handled similar to an ordinary hose with threaded couplings without liability of becoming accidentally unfastened. The outer portion of the lever forms 25 a grip or handle, and the curve thereof may be increased, if desired, sufficiently to enable the fingers of the operator to be introduced 30 between the handle and the coupling.

The lever and the yoke are adapted to exert 35 a direct longitudinal pull on the sections which are drawn together, a rubber gasket or washer 21 being interposed between the intermediate annular enlargement 17 and the end of the section 2 of the coupling. One or more rings or washers may be employed, and these 40 may be of any desired size to secure the desired joint.

40 The sections are readily uncoupled by simply swinging the operating lever from the position illustrated in full lines in Fig. 1 to that shown in dotted lines, and in coupling the sections the yoke is first arranged in the groove 45 22 between the shoulder 7 and an enlargement 23, and the lever is then swung forward or inward against the coupling to the position shown in full lines in Fig. 1.

What I claim is—

50 1. A coupling comprising two sections, one of the sections being provided with an annular shoulder, and the other having an annular

enlargement, a collar arranged on the section having the enlargement and capable of rotation, said collar being provided with means 55 for interlocking it with the said enlargement, a lever carried by the collar, and a yoke connected with the lever and engaging the shoulder, substantially as described.

2. A coupling comprising two sections, one 60 of the sections being provided with a shoulder and the other section having an annular enlargement, a collar arranged on the latter section and provided with arms interlocked with the said enlargement, a lever fulcrumed on 65 the collar, and a yoke connected with the lever and engaging the shoulder, substantially as described.

3. A coupling comprising a section provided 70 with an intermediate annular enlargement having an annular groove, a collar fitted on the said section at the outer side of the enlargement and provided with L-shaped arms engaging the groove, a lever fulcrumed on the collar, a yoke connected with the lever, and a section having a shoulder for engaging the 75 yoke, substantially as described.

4. A coupling comprising the section 1 having 80 an exterior annular enlargement provided with an annular groove, the section 2 enlarged to receive the section 1 and to form a shoulder, a collar arranged on the section 1 and provided with means for engaging the said groove, a lever fulcrumed on the collar, a yoke connected with the lever and engaging the said shoulder, 85 and a packing-ring or washer interposed between the section 2 and the enlargement of the section 1, substantially as described.

5. A coupling comprising two sections, one 90 of which is provided with a shoulder and the other having an annular enlargement, a rotatable collar arranged on the latter section and provided with arms interlocked with the said enlargement, a yoke engaging the shoulder on the other section, and means connecting the 95 yoke to the collar, substantially as described.

In testimony that I claim the foregoing as my own I have hereto affixed my signature in the presence of two witnesses.

LINVILLE V. LONG.
